UNITED STATES PATENT OFFICE.

WILLIAM ANSELM COATES, OF CHORLTON-CUM-HARDY, AND DAVID REGINALD DAVIES, OF STRETFORD, MANCHESTER, ENGLAND, ASSIGNORS TO WESTINGHOUSE ELECTRIC & MANUFACTURING COMPANY, A CORPORATION OF PENNSYLVANIA.

ELECTRICAL SWITCH GEAR.

Application filed June 18, 1921, Serial No. 478,575, and in Great Britain June 22, 1920.

- This invention relates to electrical switch gear of what is commonly known as the iron-clad type in which the various switches, conductors, instrument and other transformers which are or may be connected between the oil switch and the bus-bars are enclosed in casings usually of metal which are afterwards filled with oil or a solid insulating material.
- 10 Our invention has for its object to provide an improved construction of switch gear of the type described above in which the amount of oil insulation required is reduced.
- According to the invention, those parts of the gear which comprise fixed joints or conductors including the metallic terminals of the isolating and selector switches are disposed in receptacles which are filled with solid insulating material while only the receptacles containing the transformers and the usual oil switch are filled with oil. The isolating or disconnecting switches and the selector switches are of the plug type, the socket and the head through which the plug 25 is reciprocated being connected by an insulating tube preferably of micanite which may or may not be filled with oil.
- In carrying out the invention, three main chambers or receptacles are provided, one consisting of a comparatively long tubular chamber extending horizontally in front of the apparatus and containing the bus-bars, the conductors and cables being led in at the top and bottom of this chamber, respectively.
- 30 The second receptacle is located behind the bus-bar chamber and contains the transformers for the instruments and for the protective gear or such of these as are provided. The third receptacle is the usual oil switch tank. These receptacles are connected by a casing or casings in which the connections between the transformers and the terminals of the oil switches and isolating and selector switches are located.
- 35 The connections are preferably made of copper conductors insulated, where they pass through the walls of the various chambers or receptacles, with micanite or other tubes, the intermediate space being filled with a bituminous insulating compound. The isolating and selector switches are of the plug type, the fixed socket portion and the head through which the movable plug or plunger is passed being connected by a tube of micanite or other suitable insulating material which may or may not be filled with insulating oil. The insulating tube is preferably continued so as to enclose the operating rod of the switch.
- 40 In one form of the invention, the axes of the isolating and selector switches are arranged vertically and the socket portion of each switch is located within the chamber or receptacle containing the bus-bars.
- In another form of the invention, the axes of the isolating and selector switches are horizontal and both the plug and the socket portions are contained in a horizontal casing which communicates at its lower part in front with an orifice or orifices provided in the top of the bus-bar chamber or casing, conductors being led from the bus-bars or ends of the cables in the casing to the socket parts of the switches as desired.
- 45 To enable the invention to be clearly understood, it will now be described with reference to the accompanying drawings which illustrate, by way of example, a construction of switch gear in accordance with the invention as applied to a three-phase electrical system with split conductor protection.
- Fig. 1 is an electrical diagram of the circuits of one phase conductor of the switch gear.
- 50 Fig. 2 is a sectional side elevation of one form of the switch gear with the isolating and selector switches horizontally disposed and showing the essential elements of one phase of the system.
- 55 Fig. 3 is a front sectional elevation of the switch gear, the right-hand portion thereof being a section on the line II-II of Fig. 2, while the left-hand portion is a section on the line III-III of Fig. 2, and
- 60 Fig. 4 is a view, similar to that of Fig. 2, showing a modified form of the switch gear wherein the isolating and selector switches are vertically disposed.
- 65 Referring to the drawings, Fig. 1 clearly shows how the cables 1, having the split conductors 2, 2, are connected by means of the main oil switch 3 with either of the two sets of bus-bars 4 and 5. The conductors 2, 2 are each connected to a terminal 6 of the isolating switches 7, 7 the other terminals 8 of which are connected in turn through the series transformer devices 9, 10 to separate blocks 11 constituting one pole of the oil switch

3. The other terminal 12 of the oil switch is connected by a conductor 13 which divides at 14 to the terminals 15, 15 of the two selector switches 16, 16. The other terminals 5 17, 17 of the switches 16, 16 are respectively connected to one of the bus-bars of each set 4 and 5 by means of the conductors 18, so that either set of bus-bars may be connected to the oil switch as desired.

10 Referring now to Figs. 2 and 3, the bus-bars which comprise, for example, a set of main bars 4 and a set of auxiliary or "hospital" bars 5, are arranged, as shown, in a tubular chamber 20 which extends across 15 the front of the switch gear and advantageously comprises a number of cast or rolled metal sections secured together and supported on pedestals or standards 21. The cables 1 pass into the chamber 20 at the bottom and 20 are sealed therein at 22 in the usual manner. The cables 1 pass into the chamber 20 at the bottom and are sealed therein at 22 in the usual manner. The tubular chamber 20 is provided at the top with an opening 23 25 through which pass the connections between the cable conductors 2 and the isolating switch terminals 6 and the connections between the selector switch terminals 17 and the bus-bars 4 and 5.

30 The isolating and selector switches 7 and 16 are advantageously of the plug type, and in the construction of switch gear illustrated in Figs. 2 and 3, these switches are similar and are arranged side-by-side in substantially the same horizontal plane, being disposed in a metal casing 25 which communicates at the front with the opening 23 in the chamber 20 and extends horizontally backwards between the latter and the oil switch 35. The said casing 25 is preferably formed of associated metal sections and extends across the whole width of the switch gear, the phase conductors of which may be separated by partitions 26.

40 The plungers of the isolating and selector switches 7 and 16 are connected by rods 27 of insulating material, such as that known as bakelite, to the operating mechanism of the switches. This mechanism conveniently 45 comprises screw-and-nut gear 30 from a hand-wheel or handle 31, as shown, although any other means may be provided for reciprocating the plungers of the switches 7 and 16 to and away from the terminal sockets 6 and 17.

To the rear end of the casing 25 are attached the head or heads 33 of the oil switch or switches 3 which are supported on girders 34, 34 forming part of the framework of the 50 switch gear. The contact studs 11 and 12 of each oil switch terminate in the metal casing 35 attached within the head 33, and the oil tank 36 is supported beneath the head 33 by means of stays 37 and a beam 38 55 or in any convenient manner.

The cable conductors 2, 2 of each phase separate in the chamber 20 and are connected to strip conductors 24 attached to, and depending from, the isolating switch terminals 6. In similar manner, the strip 70 conductors 18 connect the terminals 17 of the selector switches with the bus-bars 4 and 5.

The terminals 8 and 15 of the isolating and selector switches constituting the bushes 75 or heads through which the plunger portions of the switches 7 and 16 slide are connected by means of strip conductors 40 to metal rod conductors 41 passing downwards in insulating bushings 42 through orifices in 80 the floor of the casing 25.

The terminals 11, 12 of the oil switch 3 are connected by strip conductors or the like 43 with insulating metal rod conductors 44 85 passing from the casing 35 into the casing 25 through orifices, as shown. The rod conductors 44 are, in turn, connected in the casing 25 by strip conductors 45 to rod conductors 46 passing downwards in bushings 47 in a manner similar to the conductors 41. 90

The rod conductors 41 connected to the isolating switches are connected to the series transformer devices, such, for example, as the split conductor protection transformer 9 and the instrument transformer 10 which are supported beneath the casing 25. The transformer devices are connected in turn with the rod conductors 46 which are connected to the studs 11, 11 of the oil switch. 95

The conductors 41 and 46, which are connected respectively with the terminals 15 of the selector switches 16 and the poles 12 (shown only in Fig. 1) of the oil switch are electrically connected by means of the strip conductor 13 (see Figs. 1 and 3), each pair 105 of the selector switches being connected to a rod conductor 41 by means of a strip conductor 14.

The series transformer devices 9, 10 of each phase, together with the lower ends of the conductors 41 and 46 and the electrical connections therewith, are enclosed in a tank 48 also supported beneath the receptacle 25. The isolating and selector switches 7 and 16 are encased in tubes 49 of an insulating material, such as micanite, in order to protect the said switches and the operating mechanisms from the insulating compound and to maintain a space in which the moving parts can operate. 110 115 120

A convenient position for the potential transformer, if provided, is at the front of the switch gear above the chamber 25, the cover section of which, as indicated at 50, may be suitably shaped to receive and support the tank 51 of the said transformer which is in part shown in outline at 52 (Fig. 2). The potential transformer fuses 53 are preferably also arranged in the tank 51 so as to be flooded with oil when the tank is filled 125 130

up and an insulating barrier 54 is preferably arranged between the transformer 52 and the fuses 53.

When the various transformer devices and switches have been arranged in their proper positions and all of the permanent connections have been made, the bus-bar chamber 20, the casing 25 containing the isolating and selector switches and the terminal casing 35 of the oil switch 3, that is to say, those casings which contain the permanent connections of the switch gear, including the metallic terminal parts of the isolating and selector switches, are filled with insulating material or "compound", the movable parts of the isolating and selector switches being protected by the tubes 49, which surround them. The tanks 48 are then filled with oil to the requisite level and are secured beneath the casing 25 so that the transformer devices and the connections between the conductors 41 and 46 are immersed in the oil.

Referring to the modified form of the switch gear shown in Fig. 4, to which similar reference numerals have been applied as far as possible, the isolating and selector switches 7 and 16 instead of being arranged horizontally in the casing 25 as in the form above described are vertically disposed. The protecting tubes 49 extend through the opening 23 into the bus-bar chamber 20 while the upper ends of the tubes 49 and also the screw and nut mechanism 28 and 29 are protected by a metal casing 56.

The upper parts of the switches are surrounded and protected by the compound in the casing 25 while the lower terminals are protected by the compound in the bus-bar chamber. The bevel gear is dispensed with, the operating handles 31 being attached directly to the screws 28 as shown. The connections between the isolating and selector switches 7 and 16 and the oil switch 3 including the transformer devices 9, 10 are similar to those described in connection with Figs. 2 and 3. The casing 25, however, is somewhat modified owing to the absence of the isolating and selector switches, and partitions 57 may be provided therein to reduce the size of the spaces which are filled with "compound". The potential transformer tank 51 in this modification of the switch gear is conveniently arranged midway between the chamber 20 and the oil switch 3, and as before, is supported on the top of the casing 25. The oil switch operating mechanism is indicated as a whole at 58, but as it forms no part of the present invention, it is not described in detail.

It will be seen that with the switch gear arranged in accordance with the invention, apart from the usual oil switch tank 36 and the potential transformer tank 51, only the comparatively small tanks 48 have to be filled with oil. Consequently, the quantity

of oil necessary for the switch gear is considerably reduced below that which would be required to fill the casings containing the isolating and selector switches and the various conductors and connections as well as the transformer and oil switch tanks. The protecting tubes 49 of the isolating and selector switches may, if desired, be filled with oil.

It will be understood that the switch gear may be modified in certain constructional ways without departing from the scope of the invention; for example, the bus-bar chamber 20, the casing 25 and the tanks 48 and also the potential transformer tank 36 may be arranged in different positions relatively to one another and to the oil switches 5. In some cases the bus-bars may not be provided in duplicate so that certain of the so-called selector switches are omitted, those remaining being then more properly termed isolating switches. Although a three-phase split conductor system has been described and shown on the drawings, it will be understood that the invention is in no way restricted to such systems but is applicable to single-phase or other systems of electrical distribution. It will also be obvious that, instead of providing a handle 31 for each of the isolating and selector switches, a common operating handle may be provided to operate all these switches, simultaneously, suitable means being provided for rendering either the one or the other of each pair of the selector switches inoperative so that either the bus-bars 4 or the bus-bars 5 are connected.

If desired, interlocking devices may be provided between the operating mechanisms of the oil switches and of the isolating and selector switches and certain other parts of the switch gear such as the oil switch tanks and the lid of the potential transformer tank in order to prevent danger from incorrect operation of the switch gear.

Although three cables 1 have been shown as entering the bus-bar chamber 20, it will be understood that a single three-core split conductor cable may be in some cases used.

It will be understood, furthermore, that whereas the invention has been referred to as relating to ironclad switch gear, the various casings may be formed of other metal, for instance, a non-magnetic metal when the switch gear is designed for heavy currents.

We claim as our invention:

1. Electrical switch gear comprising a housing containing molded insulating material and an enclosed switch unit substantially surrounded by the insulating material and having conducting terminals embedded therein.

2. Electrical switch gear comprising a housing containing molded insulating material, an enclosed switch unit substantially

surrounded by said material and having conducting terminals embedded therein, and an electrical device disposed exteriorly of the housing and having its terminals projecting thereinto and connected to the said conducting terminals.

3. Electrical switch gear comprising a housing containing molded insulating material, an enclosed switch unit substantially 10 surrounded by said material and having conducting terminals embedded therein, and an enclosed oil-immersed electrical device disposed exteriorly of the housing and having its terminals projecting thereinto and connected to the said conducting terminals.

4. Electrical switch gear comprising a housing containing molded insulating material, an enclosed switch unit substantially 20 surrounded by said material and having conducting terminals embedded therein, an oil-immersed electrical device disposed exteriorly of the housing and having its terminals projecting thereinto and connected to the said conducting terminals and an enclosure for the said device attached to the said housing.

5. Electrical switch gear comprising a housing containing dry insulating material, a switch unit substantially surrounded by 30 said material and having conducting terminals embedded therein, an oil-immersed electrical device disposed exteriorly of the housing and having its terminals projecting thereinto and connected to the said conducting terminals and a receptacle for enclosing the said device and being attached to, and closed by, the said housing.

6. An electrical organization comprising current conductors, an isolating switch, a 40 transformer and a circuit breaker having permanently interconnected terminals, and a substantially integral block of molded in-

sulation in which said terminals are embedded.

7. Electrical switch gear comprising a 45 housing for feed conductors, a disconnecting switch, a housing for the disconnecting switch disposed substantially normal to the housing for the feed conductors and communicating therewith, a tank suspended 50 beneath the housing for the disconnecting switch for containing oil and electrical apparatus and terminals projecting from the housing for the disconnecting switch into the said tank, the said housings being filled with 55 molded insulating material for surrounding the said conductors and the disconnecting switch.

8. Electrical switch gear comprising an enclosed switch having terminal members 60 projecting therefrom, connectors for conductively connecting the terminal members to the feed conductors, and a housing for enclosing the enclosed switch, the connectors and the feed conductors filled with molded 65 insulating material whereby the enclosed elements are substantially surrounded by the material.

9. Electrical switch gear comprising a 70 switch, an enclosure therefor, terminals projecting from the enclosure, and a housing surrounding the enclosure and filled with molded insulating material in which the enclosure and terminals are embedded.

10. Electrical switch gear comprising a 75 switch, an enclosure therefor and a casing substantially surrounding the enclosure and filled with molded insulating material.

In testimony whereof, we have hereunto subscribed our names this first day of June 80 1921.

WILLIAM ANSELM COATES.
DAVID REGINALD DAVIES.
